US00D349949S

United States Patent [19]

Formgren et al.

[11] Patent Number: Des. 349,949

[45] Date of Patent:  Aug. 23, 1994

[54] BATHTUB

[75] Inventors: Anna-Pia K. Formgren, Paris, France; William C. McKeone, Sheboygan, Wis.

[73] Assignee: Kohler Co., Kohler, Wis.

[] Term: 14 Years

[21] Appl. No.: 19,720

[22] Filed: Mar. 9, 1994

Undated, admitted prior art, ad showing a Signa/Magna bathtub.

Undated, admitted prior art, Kohler ad showing a K-1226 Overture Whirlpool tub.

Primary Examiner—James R. Largen
Attorney, Agent, or Firm—Quarles & Brady

[57] CLAIM

The ornamental design for a bathtub, as shown and described.

DESCRIPTION

FIG. 1 is a perspective view taken from the top, front and right side of a bathtub embodying our new design; FIG. 2 is a top plan view thereof;

FIG. 3 is a cross-sectional view taken on line 3—3 of FIG. 2; and,

FIG. 4 is a cross-sectional view taken on line 4—4 of FIG. 2.

The fragmentary line representations of a mounting area in FIG. 1 and of dotted line holes shown in FIG. 1 are for the purpose of illustration only, and form no part of the claimed design.

[60] Division of Ser. No. 959,508, Oct. 9, 1992, which is a continuation-in-part of Ser. No. 792,048, Nov. 8, 1991, abandoned.

[52] U.S. Cl. D23/277
